UNITED STATES PATENT OFFICE

DONALD S. BARROWS, OF ROCHESTER, NEW YORK, ASSIGNOR TO THE SYMINGTON COMPANY, OF NEW YORK, N. Y., A CORPORATION OF MARYLAND

BUFFER AND DRAFT DEVICE

Application filed December 8, 1926. Serial No. 153,268.

This invention relates to underframes for railway rolling stock and, more particularly, to a buffer and draft device adapted for connection with an associated car as a unit and designed for economical manufacture.

The principal object of my invention, generally considered, is the provision of a buffer and draft device adapted to replace the usual spring buffer housing, striking casting and cheek plates, with or without front draft lugs, on the underframe of a car, said device being formed not only for increased strength and adapted for being rigidly connected in the desired location on the car, but being so formed that moulding conditions are improved whereby the cost of manufacture is greatly decreased.

An object of my invention is the provision of a buffer and draft device formed generally as an upper casting serving as a spring buffer housing and a lower casting serving as a striking plate or coupler stop with integrally connected cheek plate portions adapted for rigid connection with associated center sills, said cheek plate portions being formed at their inner edges with or without inwardly extending draft lugs, the upper portions of said cheek plate portions being rigidly connected by an upper shelf portion which also serves for supporting and rigidly connecting with the base of the spring buffer housing.

Another object of my invention is the provision of a buffer and draft device comprising upper and lower members each integrally formed and provided with substantially horizontal web portions adapted to register and be connected by a relatively large number of rivets, the upper casting having portions for housing associated buffer springs and stems and upstanding web portions adapted for connection with the end sill and other transverse members of the car underframe, said lower portion being formed with a striking plate, transversely spaced cheek plates adapted for rigid connection with associated center sills, and draft lug portions theron, and alternatively formed with an integral carrier iron portion.

50 A further object of my invention is the

provision of a novel housing adapted for the reception of buffer springs and stems and formed with a base portion providing a large riveting area for connection with an underlying part of the car underframe, the rear 55 edge of said base portion being formed with an upstanding web portion adapted for connection with the end sill and other parts of the car underframe.

A still further object of my invention is the 60 provision of an integral striking casting provided with portions serving as cheek plates and front draft lugs, said cheek plate portions being connected at their upper edges by the shelf portion adapted to support and 65 be rigidly connected to an overlying associated buffer housing, said shelf portion being provided with forward extensions at either side thereof for increasing the riveting area, the lower edges of said cheek plates 70 being alternatively connected by an integral coupler carrier iron.

Other objects and advantages of the invention relating to the particular arrangement and combination of the various parts will become apparent as the description proceeds.

Referring to the drawings illustrating my invention, the scope whereof is defined by the appended claims:

Figure 1 is a plan of a preferred embodiment of my buffer and draft device, a portion thereof being shown in horizontal section on the line 1—1 of Figure 4, and fragmentary portions of associated underframe members being illustrated, as well as associated draft rigging, diagrammatically illustrated by dot and dash lines.

Figure 2 is a longitudinal section view on the line 2—2 of Figure 1.

Figure 3 is a front elevation of the form 90 of device shown in Figures 1 and 2.

Figure 4 is a longitudinal sectional view on the line 4—4 of Figure 3.

Figure 5 is a partial longitudinal sectional view corresponding to Figure 2 but showing 95 a modification.

Referring to the drawings in detail, like parts being designated by like reference characters and first considering the embodiment of my invention illustrated in Figures 1 to 4, 100

inclusive, there is illustrated a buffer and draft device generally designated by the reference character 1. In the present embodiment, the device 1 consists of an upper buffer casting or spring buffer housing 2 and a lower striking casting or combination coupler stop with cheek plates and front draft lugs 3. These members 1 and 2 are rigidly connected by means such as rivets 4 extending through 10 horizontal web portions thereof.

For the purpose of providing a relatively large riveting area for securely connecting the buffer housing with the striking casting 3, the top web or shelf portion 5 of the striking casting 3 not only extends between the cheek plate portions 6 rearwardly of the striking plate or coupler stop portion 7 but is continued to either side of said cheek plate portions and there may be extended forwardly of the striking plate as indicated at 8. The rear edge of the web 5 is preferably curved, as illustrated particularly in Figure 1, between the cheek plate portions 6 to economize material. The base 9 of the spring buffer housing 2 may be formed generally similar in plan except that it terminates forwardly of the rear edge of the upper web or shelf 5 of the striking casting member 3 and is continued upwardly as a substantially vertical web 10 providing a relatively great area for adequate connection with and reinforcement of the end sill 11. At a height corresponding to the top of the end sill 11, the web 10 is preferably extended horizontally as indicated at 12 for a distance corresponding to the associated buffer block or adjacent part of the car 13. From thence a vertical web 14 is preferably extended upwardly to a height corresponding to the diameter of the buffer spring housing portions 15 as well as the vertical dimension of the associated car part 13.

Each spring and stem housing portion 15 may be formed, as illustrated, generally cylindrical for the reception of the usual springs and stems (not shown), which stems, as will be understood, may be connected in a well known manner with the buffer plate (not shown) which, when the car is coupled to another car, is adapted to engage a corresponding buffer plate thereon and close up the space between the underframes. The spring housings 15 are not only connected by the base or lower web 9, the upstanding webs 10 and 14 and the connecting web portion 12 but the front edge of the web portion 9 is preferably formed with an upstanding web 16 extending only between the near sides of the buffer housing portions 15. For rigidifying the construction, the upper edge of the web 16 may be formed with a horizontally-turned web or bead 17 and the web 14 may be likewise formed with a horizontally-turned forwardly extending web or bead 18. For rigidly connecting the webs 10 and 16, longi-

tudinally extending upright webs 19 are preferably provided as indicated.

For properly holding the buffer keys (not shown), ledges or shelf portions 20 are preferably provided adjacent the key slots 21, the inwardly extending shelf portions being terminated as illustrated shortly on either side of the key slots 21. The outer shelf portions 20, however, may be extended rearwardly to join with the outer ends of the web portions 14 thereby greatly rigidifying the construction at these points. That portion of the web 14 forming the inner walls of the spring housing portions 15 may be provided with centrally positioned forwardly extending bosses 22 serving for centering the buffer springs. The construction beneath said bosses 20 is preferably rigidified by diverging web portions 23.

For securely and rigidly connecting the buffer housing member 2 to the striking casting member 3, the registering web portions 5 and 9 are connected by a plurality of rivets 4. In the preferred embodiment illustrated, two transversely extending rows of rivets and two longitudinally extending rows of rivets, said latter rows being spaced laterally with respect to the transversely extending rows of rivets, are provided, aggregating twelve rivets in all, although it is obvious that a greater or less number of rivets may be used depending upon the size of the rivets and the necessary strength of connection between the parts.

Considering now the construction of the lower member or striking casting 3, it will be seen that the cheek plate portions 6 thereof provide adequate riveting area for connection with the associated center sills 24. Said cheek plate portions are, in the present embodiment, each adapted for connection with the associated center sill by means of two vertically spaced rows of rivets 25, each row comprising five rivets although it is obvious that I do not wish to be limited to the number of rivets employed. Said cheek plate portions are illustrated as formed with slots 26 adapted for receiving an associated draft key 27, said key, as is usual, serving for connecting an associated coupler 28 and yoke 29. The rear edges of said cheek plate portions are preferably formed with inwardly extending flanges 30 serving as draft lugs cooperating with a front follower 31 and cushioning mechanism 32 illustrated diagrammatically by dot and dash lines. The draft lug portions 30 are preferably braced and reinforced with respect to the cheek plate portions 6 by means of triangular web or gusset portions 33.

In the present embodiment, I have shown those portions of the web 8 extending forwardly of the striking plate portions 7 braced with respect to portions 34 depending from said striking plate portions 7 by means of

substantially triangular web or gusset portions 35. Said depending portions 34 are formed, in the present embodiment, with pockets 36 forming bearings for trunnions 37 on carrier iron supports 38 swingingly connected with a carrier iron 39, and adapted to serve for centering the associated coupler 28.

It will be noted that the reinforcing web 16 serves, in effect, as a continuation of the striking plate portion 7 thereby improving the appearance of the combined member and increasing the strength thereof. As with the webs 9 and 16, the web 5 and the striking plate portion 7 are preferably braced and the strength of the casting increased by longitudinal webs 40, preferably registering with the webs 19, tapering rearwardly to merge into the web 5 near the rear edge thereof. A similar construction may be effected in the embodiment illustrated in Figure 5, that is, the upper or buffer housing member 2^a may be similarly positioned with respect to the lower or striking casting member 3^a with the forward edge of web 9^a, diagrammatically illustrated in dot and dash lines, flush with the striking plate portion 7^a. The only radical difference between the modification illustrated in Figure 5 and the first embodiment is that the carrier iron 39^a is integral with the depending portions 34^a from the striking plate portion instead of being swingingly connected thereto and/or the cheek plate portions 6^a, instead of being formed with front draft lugs for cooperation with the front follower used with vertical yoke attachment, may be merely formed as the front parts of Farlow cheek plates 6^a or, if desired, may be formed as complete Farlow cheek plates. In other words, if it is desired to use my buffer and draft device with Farlow attachments, that is, with draft rigging utilizing a horizontal yoke and a pair of draft keys, the integral forward draft lugs may be omitted and the cheek plate portions 6^a of the device constructed, as illustrated in Figure 5, to form the forward portions of Farlow cheek plates or all of said cheek plates. The slot portions 26^a are preferably reinforced by a rib or beading 33^a around the slot portions in said check plates.

Additional modifications with respect to the first embodiment of my invention may comprise the discontinuance of the upper web or shelf portion of the striking casting forwardly of the end sill 11^a thereby obviating cutting the end sill especially for the reception of said shelf or web portion. The longitudinally extending reinforcing webs 40^a are likewise discontinued at points adjacent the rear edge of said shelf portion 5^a. In the first embodiment of my invention, the cheek plate or draft lug portions were shown as extending on the inner surfaces of the draft sills although it is obvious that I do not wish to be restricted to such a showing. A

similar construction is applicable to the modification shown in Figure 5 and the cheek plate portions 6^a are, therefore, shown as positioned to engage and be connected to the outer surfaces or sides of the draft sills 24^a.

Although in the present embodiment, I have shown an integral carrier iron portion 39^a, it is obvious that I do not wish to be restricted to such construction as, if desired, the coupler may be supported in a manner similar to that shown in Figures 1 to 4, inclusive. If desired, a wear plate 41 may be applied over the carrier iron portion 39^a.

The foregoing description relates particularly to what may be considered as a heavy draft and buffer device to be used where great strength is required. If it is desired to reduce the weight of this device and it is permissible to sacrifice some strength and riveting area, the following modifications are preferred. The extensions 8 on the upper web or shelf portion 5 of the striking casting 3 forwardly of the striking plate 7 or the depending portions 34 on either side thereof may be omitted together with the bracing webs or gussets 35 thereby saving the weight thereof and, at the same time, sacrificing two rivets for connecting the buffer and draft castings together, as illustrated in Figure 5. The upright web 16 and its reinforcing bead or flange 17 may also be omitted and the longitudinal webs 19^a tapered forwardly to merge into the web 9^a at the front edge thereof, as indicated in Figure 5. The rearward extensions of the web 5 overlying the draft lug portions 30 may be decreased in length with the elimination of two rivets 42, together with the connecting portion of the cheek plates 6 above the upper reinforcing flanges 33. The loss of the two rear rivets 42 on said web 6 may be partially compensated for by the application of a rivet 43 disposed substantially on the longitudinal center line of the casting and adapted for connection with an angle iron, cover plate or other part of the car underframe extending between the sills at this place.

From the foregoing description taken in connection with the accompanying drawings, it will be seen that I have devised an improved buffer and draft device adapted for use and application to an associated car underframe as a unit. The construction of the device, however, is greatly facilitated by making the same in two parts and rigidly riveting said parts together. The reason for this is that smaller casting flasks may be employed thereby improving moulding conditions as well as obviating the use of an unduly large amount of sand and large dry sand cores. In other words, in place of having to mould a very cumbersome and unwieldy device, it is merely necessary to mould two relatively simple devices and cast the same. By dividing the combined buffer and draft de-

vice at the indicated line of division, improvement in moulding conditions is effected to the greatest degree without sacrificing strength of the combined article or detracting from the strength of connection with the associated car underframe.

Having now described my invention, I claim:

1. A buffer and draft device comprising members serving, respectively, as a buffer housing and striking casting with integral cheek plate portions, said striking casting being provided with an upper substantially horizontal web portion serving to connect the cheek plate portions and support the buffer housing, said buffer housing being formed with a corresponding lower horizontal web portion adapted to register with the shelf portion of the striking casting, and rivet means rigidly connecting said web portions, said buffer housing being formed at the rear edge of its base portion with an upstanding web adapted for connection with an associated end sill.
2. A buffer and draft device comprising members serving, respectively, as a buffer housing and striking casting with integral cheek plate portions, said striking casting being provided with an upper substantially horizontal web portion serving to connect the cheek plate portions and support the buffer housing, said buffer housing being formed with a corresponding lower horizontal web portion adapted to register with the shelf portion of the striking casting, and rivet means rigidly connecting said web portions, said buffer housing being formed at the rear edge of its base portion with an upstanding web adapted for connection with an associated end sill, the upper portion of said web being provided with a forwardly offset portion adapted to provide for the reception of and be connected to an associated part of a car such as a buffer block.
3. A buffer casting comprising transversely spaced compartments adapted to receive buffer springs and associated stems, a normally horizontal web portion connecting said housing portions and providing a relatively large riveting area for connecting said member with an underlying striking casting, the rear edge of said horizontal web portion being formed with an upstanding web extending the full width of the casting for providing a relatively large riveting area for connecting the same to an associated end sill of a car, said upstanding web being formed with a forwardly offset portion adapted to provide for the reception of a buffer block or the like, whereby said casting may be rigidly connected to an associated car.

In testimony whereof I affix my signature.
DONALD S. BARROWS.
